(57) **CLAIM**

The ornamental design for a pair of speakers, as shown and described.

DESCRIPTION

FIG. 1 is a front perspective view of a first speaker and a rear perspective view of a second speaker, together being a pair of speakers showing my new design;

FIG. 2 is a front perspective view of a pair of speakers thereof;

FIG. 3 is a rear perspective view thereof;

FIG. 4 is a front perspective view thereof with a flat panel computer;

FIG. 5 is a rear view thereof;

FIG. 6 is a front perspective view thereof with a laptop computer; and,

FIG. 7 is a front perspective view thereof with a traditional computer.

The broken line showing of the computers in FIGS. 4-7 is for illustrative purposes only and forms no part of the claimed design.
